UNITED STATES PATENT OFFICE

2,459,759

N-MONOCHLOROCYCLOHEXYLAMINE

Glen Alliger, Cuyahoga Falls, Ohio, assignor to
The Firestone Tire & Rubber Company, Akron,
Ohio, a corporation of Ohio

No Drawing. Application September 5, 1946,
Serial No. 695,051

1 Claim. (Cl. 260—563)

1
The subject of this invention is N-monochlorocyclohexylamine, a new chemical compound which is useful as an intermediate as, for example, in reactions with mercaptides having the formula R—S—Na in which R may be any of the usual mercaptide groups, such as an alkyl group, benzothiazyl, thiocarbamyl, etc.

The compound is prepared by adding one mol of sodium hypochlorite to 1.16 mols of cyclohexylamine. When no excess of cyclohexylamine was used, some dichlorocyclohexylamine was formed. The reaction takes place according to the following equation:

Although the reaction may be carried out at higher temperatures, a temperature below 10° C. is preferred, as the product obtained is solid and in a purer condition when such lower temperatures are employed.

At below 10° C., a yield around 96 per cent of the theoretical was obtained. The compound was white and crystalline, insoluble in water, and melted at 24—25° C.

2
Analysis for $\text{C}_6\text{H}_{12}\text{NCl}$:

Calc.: Cl, 25.53 per cent
Found: Cl, 26.93 per cent

The usual strong oxidizing properties of N-chloroamines were exhibited by this compound; e. g., it liberated iodine from potassium iodide.

What I claim is:
N-monochlorocyclohexylamine.

Certificate of Correction

Patent No. 2,459,759.

January 18, 1949.

GLEN ALLIGER

It is hereby certified that error appears in the printed specification of the above numbered patent requiring correction as follows:

Column 2, line 2, for "25.53 per cent" read *26.53 per cent*; and that the said Letters Patent should be read with this correction therein that the same may conform to the record of the case in the Patent Office.

Signed and sealed this 16th day of August, A. D. 1949.
